RATCHET WRENCH WITH OFFSET HANDLE

Franklin J. Teichmeier, Rte. 2, Ravenna, Nebr. 68869

Filed Aug. 14, 1970, Ser. No. 24,504

Term of patent 14 years

Int. Cl. D8—05

U.S. Cl. D8—25

FIG. 1 is an elevation of a first side of the ratchet wrench with offset handle of this invention.

FIG. 2 is an end view of the wrench as seen looking from the left side of the wrench of FIG. 1.

FIG. 3 is a top plan view of the wrench.

FIG. 4 is a bottom plan view of the wrench.

FIG. 5 is a side elevation of a second side of the wrench opposite to the side shown in FIG. 1.

I claim:

The ornamental design for a ratchet wrench with offset handle, as shown and described.
